Primary Examiner—Brian N. Vinson
Attorney, Agent, or Firm—Robert T. Johnson[57] **CLAIM**

The ornamental design for a pedestal for mounting a septic pump control panel housing, as shown and described.

DESCRIPTION

FIG. 1 is a front elevational view of a first embodiment of an ornamental design for pedestal for mounting a septic pump control panel housing, showing my new design; FIG. 2 is a right side elevational view thereof; FIG. 3 is a rear elevational view thereof; FIG. 4 is a left side elevational view thereof; FIG. 5 is a top plan view thereof and; FIG. 6 is a bottom plan view thereof; FIG. 7 is a front perspective view of the ornamental design for pedestal for mounting a septic pump control panel housing; and, FIG. 8 is a rear elevational view of a second embodiment thereof, the only difference from the first embodiment residing in the appearance of the rear elevation. The broken-line disclosure in the views is for illustrative purposes only and forms no part of the claimed design.
